[57] CLAIM

The ornamental design for an egg carton, substantially as shown and described.

DESCRIPTION

FIG. 1 is a top front perspective view of an egg carton showing my new design;
FIG. 2 is a top, rear perspective view showing the end not seen in FIG. 1;
FIG. 3 is a perspective view similar to FIG. 1 but taken from the front;
FIG. 4 is a bottom perspective view showing the bottom, front and one end;
FIG. 5 is an exterior perspective view of the carton in an open position;
FIG. 6 is a view similar to FIG. 5 but taken from the opposite side;
FIG. 7 is a view similar to FIG. 5 but taken more from the front;
FIG. 8 is an exterior perspective view of the carton in an open position taken from one end; and
FIG. 9 is a plan view of the interior of the carton in an open position.
